Paul Sinclair,
INVENTOR.

BY

Geo. P. Kimmel,
ATTORNEY.

UNITED STATES PATENT OFFICE.

PAUL SINCLAIR, OF WILLIAMSPORT, PENNSYLVANIA, ASSIGNOR TO SINCLAIR HAIR CURLER COMPANY, OF WILLIAMSPORT, PENNSYLVANIA.

HAIR CURLER.

Application filed May 6, 1922. Serial No. 559,019.

To all whom it may concern:

Be it known that I, PAUL SINCLAIR, a citizen of the United States, residing at Williamsport, in the county of Lycoming and State of Pennsylvania, have invented certain new and useful Improvements in Hair Curlers, of which the following is a specification.

The invention relates to a hair curler and more particularly to the class of flexible hair crimpers or wavers.

The primary object of the invention is the provision of a device or article of this character, wherein the body thereof is formed with plural pliable or flexible cores having enveloping the same a covering and these cores covered are held in a braided sheath so that the device or article in its completed form will be relatively flat, while the tips thereof are so constructed and arranged to prevent the ends of the sheath from ravelling or the cores working therefrom, the device or article being readily flexible so that it can be bent into the desired shape for the crimping, waving or otherwise arranging of the hair.

Another object of the invention is the provision of a device or article of this character, wherein the construction thereof is novel in form, to assure maximum wearing quality, easy application for the dressing of the hair and will avoid any discomfort in the use thereof to the user.

A further object of the invention is the provision of a device or article of this character, which is extremely simple in its construction, practical, thoroughly efficacious in its purpose, strong, durable, neat and attractive in appearance, and inexpensive to manufacture.

With these and other objects in view the invention consists in the features of construction, combination and arrangement of parts, as will be hereinafter more fully described, illustrated in the accompanying drawings and pointed out in the claim hereinto appended.

In the accompanying drawings:—

Fig. 1 is a plan view of a curler, waver or crimper, constructed in accordance with the invention,

Fig. 2 is a view similar to Fig. 1 showing portions of the sheath and enveloping coverings for the cores partly broken away,

Fig. 3 is a sectional view on the line 3—3 of Fig. 2,

Fig. 4 is a view similar to Fig. 2 showing a slight modification of the invention,

Fig. 5 is a sectional view on the line 5—5 of Fig. 4.

Similar reference characters indicate corresponding parts throughout the several views in the drawings.

Referring to the drawings in detail, particularly to Figs. 1 to 3, inclusive, A designates generally a hair curler, crimper or waver, constructed in accordance with the invention and comprises several strands or single lengths of wires 5, preferably made from copper, brass or lead, having the required flexibility to permit the bending thereof for the purposes intended of the invention. These wires 5 are covered with an insulation 6, preferably of rubber, yet the covering may be of other desirable material and in the use of the several wires is independent of each other.

The wires and covers 6 are of the required length, it being understood that the same may be long or short as the occasion may require and are disposed in contacting parallel relation to each other as is shown in Figs. 2 and 3 of the drawing.

Disposed relatively taut about the several coverings 6 of the cores formed by the latter and the wires 5 is a sheath 7 of woven, braided or otherwise formed fabric constituting a housing, the opposite ends being outwardly tapered as at 8 while the terminals of the said housing are closed through the medium of tips 9, preferably formed by shellac or other hardened substances. The tapered ends of the device or article are effected by compacking the insulated end portions of the wires 5 in the weaving process of the housing 7, while the disposition of the wires 5 with the insulation 6 thereon in said housing presents a flattened body to the curler, crimper or waver, thereby rendering the same more effective for its purpose in use.

In Figs. 4 and 5 of the drawing, there is shown a slight modification of the device or article, wherein there is employed three wires 10 forming the cores, which are arranged in close parallel relation to each other and are confined collectively in an insulated covering 11, while surrounding the

latter is the housing 12 of woven fabric. By this particular construction the device or article is wider than that shown in Figs. 1, 2 and 3 of the drawing.

- 5 It is to be understood that any number of wires may be employed and the same may be separately insulated or collectively in the manufacture should it be found desirable.
- 10 By reason of the constructions herein described, it will be seen that the device or article tapers at its end portions from the central widened portion and since the greater stress or pull will be intermediate 15 the ends, the said device or article will be prevented from being pulled apart or dismembered as is well understood.

From the foregoing, it is thought that the construction and manner of use of the device will be obvious, therefore a more extended 20 explanation has been omitted.

What is claimed is:—

A device or article of the character described, comprising a plurality of flexible cores arranged in parallelism with each 25 other, means enveloping the cores, a woven fabric housing concealing said means and tips closing the ends of said housing, the means covering the cores being compressed within the housing at the end portions there- 30 of for outward tapered formation thereto.

In testimony whereof, I affix my signature hereto.

PAUL SINCLAIR.
